UNITED STATES PATENT OFFICE.

EDMUND S. CHURCH, OF CHICAGO, ILLINOIS, ASSIGNOR TO AUTOMATIC CARBURETOR COMPANY, OF CHICAGO, ILLINOIS, A CORPORATION OF ILLINOIS.

FUEL-REGULATING DEVICE FOR EXPLOSIVE-ENGINES.

1,308,145.

Specification of Letters Patent.

Patented July 1, 1919.

Application filed January 6, 1916. Serial No. 70,564.

To all whom it may concern:

Be it known that I, EDMUND S. CHURCH, a citizen of the United States, and a resident of Chicago, in the county of Cook and State 5 of Illinois, have invented certain new and useful Improvements in Fuel-Regulating Devices for Explosive-Engines, of which the following is a full, clear, and exact description.

10 The invention relates to fuel regulating devices for explosive engines. One object of the invention is to provide an improved regulating device which is sensitively responsive to variations in suction in the in- 15 take pipe.

Another object of the invention is to provide an improved regulating device which is simple in construction and efficient in operation.

20 The invention consists in the several novel features hereinafter set forth and more particularly defined by claims at the conclusion hereof.

In the drawings: Figure 1 is a vertical 25 section of a carbureter and pipe leading to the engine, equipped with the improved regulating device, which is shown in position assumed when engine is running with a light load. Fig. 2 is a section of the regulating device. Fig. 3 is a section taken on line 3—3 of Fig. 2.

The regulating device is illustrated as applied to the branch 4 of a manifold 5 leading to the cylinders of the engine. A carbureter, which may be of any suitable construction, is connected to deliver combustible mixture to pipe 4. The carbureter illustrated comprises a suitable casing 10 in which a chamber 11 is formed for containing liquid fuel supplied thereto by a pipe 12. A column of liquid is maintained at a predetermined level in chamber 11 by a float 14, which is provided with a stem 15 which is vertically guided in the cover 16 of the casing. This float is operatively connected to an admission valve 17 which controls the supply of liquid to the chamber 11. Valve 17 is provided with a guide 18 at its upper end which slides on a guide-rod 19 and is 50 operatively connected to the float by the lever 20, which has a forked end 21 in engagement with the stem of valve 17. Lever 20 is pivoted to the casing, at 22, and its other end is pivotally connected, as at 23, to a lug 24 on the float. The float serves to

automatically maintain a column of liquid at a predetermined level.

A nozzle 25 terminates slightly above the level of the liquid in chamber 11, so that the liquid will not overflow from the nozzle 25 by gravity and will be delivered from the nozzle by suction. The liquid is delivered to the nozzle by a duct 26 formed in the casing. A needle valve 27 serves to regulate the maximum flow of liquid to the nozzle 25. 65 A choke tube 34 is formed in the casing around nozzle 25 and extends above the upper end of the nozzle. A primary air inlet 35 is formed in the bottom of the casing to admit air into said tube and around the 70 nozzle. An intake 30 for auxiliary air is connected to the chamber around the tube 34 and this intake is controlled by a valve 31 which is adapted to fit against a seat 32 and is yieldingly held in closed position by a 75 suitable spring 33. Air admitted through intake 30 passes through the chamber around tube 34 and thence to the throttle 39 for controlling the volume of mixed air and gas supplied to the engine. Air passing through 80 tube 34 exerts a suction upon the liquid in the nozzle 25 and causes the liquid to be lifted out of the nozzle and mixed therewith, and this mixture, when the suction is sufficient to open valve 31, is mixed with the 85 auxiliary air from intake 30 in the chamber 37 above tube 34, to which the pipe extension 10^a, is connected. The mixture passes from chamber 37 into pipe 10^a. A throttle 90 valve 39 pivoted in pipe 10^a, controls the volume of fluid supplied to the engine. The throttle valve is manually controlled and any suitable connection may be used for shifting it to vary the volume of the fluid supply. 95

The improved automatic device for regulating the mixture according to the suction of the fluid passing to the engine, comprises a nipple or hollow plug 50 which has a screw-threaded portion 51 at its inner end which is adapted to pass through and be secured in the wall of branch-pipe 4 of the intake manifold. A plunger 52 is slidably fitted in the outer portion of nipple 50. A diaphragm has its central portion secured to said plunger and its marginal portion secured to a casing 54 which is secured on the outer end of nipple 50. Casing 54 is formed of members 55 and 56 which may be formed of sheet metal. The marginal portion of 100 105 110

one casing is lapped around the other, the margin of the diaphragm being securely clamped between the members. Member 55 is shaped or extended outwardly from the 5 plunger 52 to form a vacuum chamber 57 on the outer side of the diaphragm. This chamber is in communication with the inside of pipe 4 through a small pipe 58 which is fixedly secured in the head of plunger 52, 10 so that chamber 57 and the passage in the intake 4 are in constant communication and so the branch pipe 4 and chamber 57 will be under the same suction. A spring 59 between the diaphragm and member 55 is provided to yieldingly retain the plunger 52 and diaphragm in normal position shown in Fig. 2. In this position, the spring has substantially reached the limit of its expansion 15 and is not effective to shift the plug inwardly. An opening 60 in member 55 admits air to the inner side of the diaphragm and to the chamber between the diaphragm and casing-member 56. Plunger 52 is provided with air ports 61 adapted to be shifted 20 into registry with air ducts 62 disposed in nipple 50 and inwardly of the diaphragm, to admit air from the outside to the nipple 50.

The regulating device may be rendered 30 inoperative to admit air to the intake manifold, as may sometimes be desired in starting the engine, by a suitable closure 63 which is pivoted to casing member 56, so that it may be swung into position to close opening 60.

Normally, the regulating device will be in the position shown in Fig. 2. In starting, the opening 60 may be closed if necessary to prevent the mixture passing to the 40 engine from being diluted by the regulating device. In practise, however, this is seldom necessary, except where there is extreme difficulty in starting. When the engine is running and the opening 60 is uncovered, 45 the regulating device will operate automatically in response to variations in suction in the branch-pipe 4 of the intake manifold. When the engine is idling *i. e.*, running without a substantial load, it will be running at 50 comparatively high speed and cause a high degree of suction in the intake, because the throttle 39 is then usually set to permit a comparatively small volume of fluid to pass to the engine. As a result of this high suction, which is communicated to the chamber 57, diaphragm 53 will move plunger 52 outwardly to bring ports 61 and ducts 62 into registry more or less, according to the degree 55 of suction in the vacuum chamber 57. As a result, the mixture passing to the engine 60 will be diluted, because at such time, the load upon the engine does not require a rich mixture. When the engine is running at average speed, under a normal load, for example, when used to drive an automobile 65

and the latter is running on level ground at average speed, at which time the throttle will be open more than when the engine is idling, there will be sufficient vacuum in chamber 57 to cause the diaphragm to operate plunger 52 to admit additional air to the intake to form a substantially perfect mixture, as shown in Fig. 1. When the load upon the engine is abnormal *e. g.*, when the automobile is being driven up an incline, 70 the suction in the intake is comparatively low in degree, because the throttle at such time is set to allow full or greater volume of flow of fluid to the intake and at such time, the suction will be reduced in the vacuum chamber 57, so that the admission of air through the regulating device will be partially or wholly cut off, thus resulting in enriching the mixture responsively to the 75 load upon the engine. 80

It will be observed that the ports 61 are peripheral and as the plunger 52 slides outwardly the open area of the ports will gradually increase and after the ports 61 have passed into full registry with the ports 62, further outward movement will cause a gradual restriction of the air inlet. As a result, as the speed of the engine increases to a point above normal, running with a normal load, the supply of air will be gradually 90 reduced to gradually enrich the mixture so that greater speed can be attained. 95

The invention thus exemplifies an improved automatic regulating device whereby the mixture in transit to the engine will be 100 diluted or enriched responsively to the variation of suction of the mixture after it has passed the throttle to automatically adapt the mixture for the load upon the engine. The improved device operates independently of 105 the carbureter, *i. e.*, does not vary the operation of the carbureter parts. 110

The regulating device is simple in construction and can be readily attached to the intake of an engine of usual construction 115 without modification or reconstruction of the carbureter.

The invention is not to be understood as restricted to the details set forth, since these may be modified within the scope of the appended claims, without departing from the spirit and scope of the invention. 115

Having thus described the invention, what I claim as new and desire to secure by Letters Patent, is:

1. A regulating device for controlling the supply of a fluid to explosive engines comprising a nipple having means at one of its ends adapted for attachment to the intake of an engine, a tubular valve slidably mounted in said nipple, a diaphragm secured to the outer end of said valve, an admission port controlled by said valve, a suction chamber disposed at the outside of the diaphragm, and means secured to the valve and 125 130

diaphragm extending through the nipple and communicating with said chamber and the chamber in the intake.

2. A regulating device for controlling the supply of a fluid to explosive engines comprising a nipple having means at one of its ends adapted for attachment to the intake of an engine, a tubular valve slidably mounted in said nipple, a diaphragm secured to the outer end of said valve, an admission port controlled by said valve, a suction chamber disposed at the outside of the diaphragm, and a tube extending through said diaphragm and through said nipple having a duct communicating with said chamber and the intake.

3. A regulating device for controlling the supply of a fluid to explosive engines comprising a nipple having means at one of its ends adapted for attachment to the intake of an engine, a tubular valve slidably mounted in said nipple, a diaphragm secured to the outer end of said valve, an admission port controlled by said valve, a suction chamber disposed at the outside of the diaphragm, means secured to the valve and diaphragm extending through the nipple and communicating with said chamber and the chamber in the intake, and a supporting ring between the nipple and the diaphragm having an inlet therein.

EDMUND S. CHURCH.
